UNITED STATES PATENT OFFICE

SAMUEL WILEY, OF METUCHEN, NEW JERSEY

FLARE

Application filed August 16, 1929. Serial No. 386,408.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to a flare of the type which is launched from aircraft for the purpose of signaling or illumination.

The improvements in the flare forming the subject of this invention are directed to the 10 formation of a parachute container which is detachably associated with a light case through a novel release mechanism which will permit the insertion and withdrawal of the parachute without fouling and which will 15 serve as a launching tube.

With the foregoing and other objects in view, the invention resides in the novel arrangement and combination of parts and in the details of construction hereinafter 20 described and claimed, it being understood that changes in the precise embodiment of the invention herein disclosed may be made within the scope of what is claimed without departing from the spirit of the invention.

25 A practical embodiment of the invention is illustrated in the accompanying drawings, wherein:

Fig. 1 is a view in elevation of the improved flare, showing the parachute container in section;

Fig. 2 is a view in side elevation taken at right angles to Fig. 1;

Fig. 3 is a view partly in elevation and partly in section, showing the separation of the light case from the container;

Fig. 4 is a view in side elevation taken at right angles to Fig. 3; and

Fig. 5 is an enlarged detail sectional view of the fastener.

40 Referring to the drawings by numerals of reference:

The flare comprises a cylindrical light case 5 containing an illuminating composition 6 and arranged to be suspended during flight 45 by means of a parachute 7 which is secured by means of a cable or cord 8 to a block 9 fixed in the upper end of the light case. The parachute when folded is housed in a container 10 which is inserted within and spaced 50 from a tubular extension 11 on the upper end

of the light case attached thereto in any suitable manner, specifically by screws 12 entering the blocks 9. The end cover 13 of the parachute container projects beyond the wall thereof and is formed with outwardly flared sides 14 designed to fit over the rolled edge 15 of the tubular extension 11 and establish a tight fitting closure for the light case.

55 The parachute container 10 may be made of flexible material such as paper, cloth or other flexible fabric or of rigid material, such as metal, fiber or the like. The substitution of flexible material for rigid material in containers of this character is desirable as the flares are used with horizontal racks as well as with vertical racks.

60 The light case and parachute container are separably fastened together adjacent the upper end of the flare for convenience in releasing the flare from launching apparatus mounted in aircraft. The fastening device consists of a depending channelled hasp member 16 secured to the cover 13 of the parachute container and spaced sufficiently from the wall of the container to clear the tubular extension 11 of the light case when the flare is 65 assembled. The sides 17 of the hasp (see Figs. 3 and 5) are provided with aligned openings or recesses 18 and for convenience in establishing the recesses, the corresponding portion 70 of the face plate 19 of the channelled hasp may be cut away.

75 A staple or keeper 20 provided on the extension 11 is formed to enter the channel in the hasp and it is positioned for alignment with the recesses 18 when the edge 15 of the extension is in place against the cover 13. With the parts thus arranged, a key 21 inserted through the recesses 18 and within the keeper will prevent separation of the light case from 80 the parachute container.

85 In order that the key may be retained firmly in place until deliberately withdrawn a thin metal plate 22 (see Figs. 3 and 5) is placed between it and the keeper being secured to the outside of the key by having its central portion pressed into an aperture 23 in the key. The ends 24 of the plate 22 extend beyond the side edges of the keeper and are bent away from the key, the angle thus made determin- 90

ing the force required to withdraw the key from the keeper. Withdrawal of the key may be effected from either side and to this end an aperture 25 is provided in each end of the key for attachment of a release cable 26.

5 The upper corner portions of the key are equally cut away as at 27, providing an intermediate portion 28 for engaging and supporting the keeper when the under edge of the key rests on the floor of the recesses 18 in the sides 10 of the hasp member. A cam 29 is secured to the extension 11 within the keeper and is positioned opposite the lower edge of the key when the parachute container and the light 15 case are fastened together. A pin 30 fixed in the lower corner at either end of the key engages the cam upon withdrawal of the key and after the intermediate portion 28 has cleared the keeper. In the event that the light 20 case does not become separated from the parachute container through its own weight when no longer restrained by the portion 28 of the key, the engagement of the pin 30 with the cam 29 will positively insure separation of the 25 members.

The lower extremity of the hasp member 16 constitutes a supporting means for the flare and is pointed to facilitate insertion in the launching apparatus of the aircraft.

30 The flare is stored and transported in the assembled position shown in Fig. 1 and is placed without alteration in the launching apparatus. The withdrawal of the key 21 permits the separation of the light case, as shown 35 in Fig. 3, the parachute container remaining in place. As the light case descends, the cord 8 and the shrouds 31 are carried along and when taut, cause the parachute to be extracted from its container. Ignition of the illuminating composition 6 may be effected in any well-known manner.

I claim:

1. A flare embodying a light case having a tubular extension at one end thereof, a 40 parachute container insertable in the extension and spaced therefrom, a cover on the outer end of the container projecting beyond the extension to grip the edge thereof, a flare supporting member carried by the cover 45 of the container and disposed along the outside of the extension and means for separably fastening the light case to the supporting member.

2. A flare embodying a light case having a tubular extension at one end thereof, a 50 parachute container insertable in the extension and spaced therefrom, a cover on the outer end of the container projecting beyond the extension to grip the edge thereof, a 55 flare supporting member carried by the cover of the container and means for separably fastening the light case to the supporting member.

3. A flare embodying a light case having 60 a tubular extension at one end thereof, a

parachute container insertable in the extension and spaced therefrom, a cover on the outer end of the container projecting beyond the extension to grip the edge thereof, a flare supporting member carried by the cover of the container and means for separably fastening the light case to an element of the 70 parachute container.

4. A flare embodying a light case having a tubular extension at one end thereof, a 75 parachute container insertable in the extension and spaced therefrom, a cover on the outer end of the container projecting beyond the extension to grip the edge thereof and a flare supporting member carried by the cover 80 of the container.

5. A flare embodying a light case having a hollow extension at one end thereof, a 85 parachute container insertable within the extension and spaced therefrom, a cover on the outer end of the container projecting to close the extension and means for separately fastening the light case and parachute container.

6. A flare embodying a light case having a 90 hollow extension at one end thereof, a parachute container insertable within the extension and spaced therefrom and a cover on the outer end of the container projecting to close the extension.

7. In a flare, a light case having a hollow extension, a parachute container insertable within the extension and forming a closure therefor, a channelled hasp formed with an opening secured to the container and disposed along the outside of the extension, a keeper on the extension movable in the channel of the hasp to a position in line with the opening therein, a key having its upper corners cut away, insertable through the opening in the hasp behind the keeper, a flexible member carried by the key for engaging the sides of the keeper, a cam on the extension 100 positionable in line with the key and a cam follower on each end of the key.

8. In a flare, a light case having a hollow extension, a parachute container insertable within the extension and forming a closure therefor, a channelled hasp formed with an opening secured to the container and disposed along the outside of the extension, a keeper on the extension movable in the channel of the hasp to a position in line with the opening therein, a key insertable through the opening in the hasp behind the keeper, and a flexible member carried by the key for 110 engaging the sides of the keeper.

SAMUEL WILEY.
